UNITED STATES PATENT OFFICE

JAMES G. BLUNT, OF SCHENECTADY, NEW YORK

MEANS FOR SUPPORTING LOCOMOTIVE AUXILIARIES

Application filed November 1, 1929. Serial No. 404,069.

This invention relates generally to means for supporting auxiliaries on the shells of locomotive boilers.

Heretofore, the various brackets for supporting on a locomotive boiler shell, such as auxiliaries as air pumps, feed water heater pumps, air reservoirs, exterior pipes, etc., have been fastened to the boiler shell by studs, which studs have been required to bear the full weight of the auxiliaries and their brackets, and are consequently subjected to stresses in service which frequently produce leaks.

An object of the present invention is to provide means enabling the auxiliaries disposed on the outside of locomotive boilers to be supported thereon without the use of studs or bolts penetrating the boiler shell.

Another object of the present invention is to provide means for supporting on a boiler shell the weight of auxiliaries and their attaching brackets, whereby the studs, or the like, used to fasten the brackets to the boiler shell are not subjected to injurious strains.

Other objects of the invention will herein-after readily appear.

The improvement claimed is hereinafter fully set forth.

In the accompanying drawings: Figure 1, is a side view in elevation of a portion of a locomotive boiler having the invention applied thereto; Fig. 2, a vertical transverse section taken on the line II-II of Fig. 1; Fig. 3, a vertical transverse section taken on the line III-III of Fig. 1; Fig. 4, a perspective view of one of the take-up blocks attached to the upper ends of the strap sections; Fig. 5, a side view in elevation of a portion of a boiler having a modified form of the invention applied thereto; Fig. 6, a transverse vertical section, taken on the line VI-VI of Fig. 5; and, Figs. 7 and 8, fragmentary vertical sections, showing two further modifications of the invention.

In the practice of the invention referring descriptively to specific embodiments thereof which have been selected for exemplification herein, the boiler shell 10, supports on its opposite sides a feed water heater bracket 11, and a reverse gear bracket 12.

The feed water heater bracket 11, is formed

with a rear wall 11a, curved to fit the boiler shell, and two parallel vertical end walls 11b, which project laterally from the rear wall. Projecting laterally outward from the top and the bottom of each end wall is a lug 11c for the attachment of a feed water heater not shown. A pair of spaced knuckles 11d, project above the rear wall, and are provided with suitable openings in which is fitted a bolt 11e, adapted to connect the bracket to a supporting strap. The bracket is fastened to the boiler shell by studs 11f, which pass through suitable openings in the rear wall 11a of the bracket and are screwed into the boiler shell.

The reverse gear bracket 12, has a rear wall 12a, curved to fit the boiler shell, and spaced knuckles 12b, and a bolt 12c, similar to those of the feed water heater bracket 11. It is fastened to the boiler shell similarly to the feed water heater bracket 11, by studs 12d.

For relieving the studs 11f and 12d of the feed water heater and reverse gear brackets of the major portion of the weight of the brackets and the attached auxiliaries, a strap 13, connected at each end to one of the brackets and passing over the top of the boiler shell, is employed. This strap comprises two sections 13a and 13b, connected together at their upper ends by a take-up device 13c. The lower end of each strap section is provided with an eye 13d, disposed between the knuckles of one of the brackets and receiving the bolt thereof. The upper end of each strap section is formed with a hook 13e adapted to engage one of the blocks 13g and to fit in a recess 13f therein. Each block 13g is provided with two holes 13h, through which pass take-up bolts 13i. Suitable nuts 13j threaded on the ends of the bolts 13i, are adapted to be adjusted so as to draw the upper ends of the strap sections together and thus cause the strap 13 to support on the boiler shell the major portion of the weight of the brackets 11 and 12 and the auxiliaries which they carry, thus relieving the bracket studs of undesirable strains.

At the forward end of Figure 1, and in Figure 3, are shown means similar to those just described, for supporting combined run-

ning board and air drum brackets 14, to each of which is fastened a running board 14a and an air drum 14b.

In Figures 5 and 6, of the drawings, is shown a modified form of construction wherein are employed a strap 15, which passes over the top of the boiler shell, and a strap 16, which passes under the bottom of the boiler shell. The strap 15 is made continuous from end to end and has at each end a loop 15a, one connected by a bolt 17a, to a feed water heater bracket 17, and the other, by a bolt 18a, to a reverse gear bracket 18. The strap 16 has an eye 16a, at one end by which it is secured to the reverse gear bracket 18 by a bolt 18b. The other end of the strap 16 is provided with a loop 16b, which engages a U-bolt 17b attached to the feed water heater bracket 17. Nuts 17c, threaded on the bolt 17b, serve as a take-up enabling the straps 15 and 16 to be tightened as desired.

If desired, one or more suitable studs 19, passing through the boiler shell, and slots 19a in the brackets, may be employed to additionally secure the brackets 17 and 18 to the shell.

In Figure 7 of the drawings, is shown another modified form of construction wherein the bracket 17 for an auxiliary, is additionally supported on the boiler shell by a relatively short strap 20, connected at one end by a bolt 17a, to the bracket 17, and at its other end by a bolt 21a, to a hanger bracket 21, secured to the boiler shell by rivets 21b.

In Figure 8 is shown a further modification which differs from that shown in Figures 5 and 6 in that instead of employing the bottom strap 16, the brackets 17 and 18 are respectively, formed with vertical flanges 17e and 18d, which are connected by a horizontal bolt 22, having nuts 22a at each end to provide for take-up.

Although supports for certain auxiliaries have been described, it is to be understood that the invention is not limited to such particular auxiliaries, but is adapted for supporting all such auxiliaries as it may be desirable to support on the sides of a boiler. Further, it is within the contemplation of the invention to fasten the ends of the strap to the auxiliaries rather than the bracket.

It will be noted that in the foregoing description the term "strap" has been employed in various places to denote exemplifications of the hanger referred to in the various claims appended hereto. While the strap formation as shown in the drawings and described in the specification is a preferred type of hanger, it will be obvious that if "strap" is understood in its narrower sense as a flat flexible band, "hanger" is a broader term, and would include not only the strap of such limitation, but also chains, cables, bars, and the like, that are well-known and of every day use in the capacity of a strap.

While some of the various forms of construction have been described and shown, it is obvious that many variations in procedure, form, arrangement, and construction of parts, may be resorted to, and the invention, therefore, is not limited to the particular embodiments disclosed, but includes such changes and modifications as come within the spirit and scope of the invention as set forth in the appended claims.

The invention claimed and desired to be secured by Letters Patent, is:

1. In a locomotive the combination of a boiler shell; an auxiliary disposed outside of the boiler shell; a hanger above the auxiliary supported entirely above the auxiliary by the shell with the capacity to swing at its lower end and carrying at least a portion of the weight of the auxiliary, whereby the hanger will be under tension strain only, when supporting weight of the auxiliary; and means disposed below the hanger to prevent its swinging, but leaving the hanger free to act under tension strain only.

2. In a locomotive, the combination of a boiler shell; an auxiliary disposed outside of the boiler shell; a hanger supported by the boiler shell and carrying at least a portion of the weight of the auxiliary; and adjustable means for regulating the amount of the weight of the auxiliary borne by the hanger.

3. In a locomotive, the combination of a boiler shell; a bracket member disposed outside of the boiler shell; an auxiliary member attached to the bracket member; a hanger above the members supported entirely above the members by the shell with the capacity to swing at its lower end and carrying at least a portion of the weight of the members, whereby the hanger will be under tension strain only, when supporting said weight; means attaching the hanger to one of said members; and means disposed below the hanger to prevent its swinging, but leaving the hanger free to act under tension strain only.

4. In a locomotive the combination of a boiler shell; an auxiliary disposed outside of the boiler shell; a hanger above the auxiliary supported entirely above the auxiliary by the shell with the capacity to swing at its lower end and carrying a portion of the weight of the auxiliary, whereby the hanger will be under tension strain only, when supporting weight of the auxiliary; and means fastening the auxiliary to the boiler shell for supporting the remainder of the weight and to prevent the hanger from swinging, but leaving the hanger free to act under tension strain only.

5. In a locomotive, the combination of a boiler shell; a device disposed outside of the boiler shell; a first means for attaching the device to the boiler shell; and a second

means comprising a hanger above the device supported entirely above the device by the shell with the capacity to swing at its lower end and carrying at least a portion of the weight of the device, whereby the hanger will be under tension strain only, when supporting weight of the device, said first attaching means acting to prevent the hanger swinging, but leaving the hanger free to act under tension strain only.

6. In a locomotive, the combination of a boiler shell; a plurality of devices disposed exterior of the boiler shell at least one being on each side thereof; and means connected to the devices, passing over the top of the boiler shell and supporting on the boiler shell at least a portion of the weight of the devices.

7. In a locomotive, the combination of a boiler shell; a plurality of devices disposed exterior of the boiler shell at least one being on each side thereof; means connected to the devices, passing over the top of the boiler shell, and supporting on the boiler shell at least a portion of the weight of the devices; and means associated with said first mentioned means, and adapted for adjustment to control the amount of weight of the devices, supported on the shell by the first mentioned means.

8. In a locomotive, the combination of a boiler shell; a plurality of brackets for supporting auxiliaries, disposed at least one on each side of the boiler shell; and a strap passing over the top of the boiler shell and connected to the brackets for supporting at least a portion of the weight thereof.

9. In a locomotive, the combination of a boiler shell; a plurality of brackets for supporting auxiliaries, disposed at least one on each side of the boiler shell; means passing over the top of the boiler shell and connected to the brackets for supporting at least a portion of the weight thereof; and means for regulating the amount of weight imposed on the first mentioned means.

10. In a locomotive, the combination of a boiler shell; a plurality of brackets adapted to support auxiliaries, and disposed at least one on each side of the boiler shell; and means comprising sections, passing over the top of the boiler shell and connected to the brackets, said means comprising a take-up device for connecting the sections.

11. In a locomotive, the combination of a boiler shell; a plurality of brackets adapted to support auxiliaries, and disposed at least one on each side of the boiler shell, each bracket having formed therein means for attachment to a hanger; and a hanger passing over the top of the boiler shell and secured to the attaching means of the brackets.

12. In a locomotive, the combination of a boiler shell; a plurality of brackets adapted to support auxiliaries, and disposed at least

one on each side of the boiler shell, one bracket comprising a pair of spaced knuckles and a pin connecting the same; and means passing over the top of the boiler shell and comprising a take-up device and an eye passing around the pin.

13. In a locomotive, the combination of a plurality of auxiliaries disposed outside the boiler shell at least one on each side thereof; a hanger passing over the top of the boiler shell and supporting thereon at least a portion of the weight of two auxiliaries disposed on opposite sides of the boiler shell; and means passing under the bottom of the boiler shell and cooperating with the hanger to maintain the auxiliaries supported thereby in fixed position.

14. In a locomotive, the combination of a plurality of auxiliaries disposed outside the boiler shell at least one on each side thereof; a hanger passing over the top of the boiler shell and supporting thereon at least a portion of the weight of two auxiliaries disposed on opposite sides of the boiler shell; and means passing under the bottom of the boiler shell and cooperating with the hanger to maintain the auxiliaries supported thereby in fixed position, said means including a take-up device.

15. In a locomotive, the combination of a plurality of auxiliaries disposed outside the boiler shell at least one on each side thereof; a hanger passing over the top of the boiler shell and supporting thereon at least a portion of the weight of two auxiliaries disposed on opposite sides of the boiler shell; and a tie-bar passing under the bottom of the boiler shell and cooperating with the hanger to maintain the auxiliaries supported thereby in fixed position.

16. In a locomotive, the combination of a plurality of bracket members disposed outside of the boiler shell at least one on each side thereof; an auxiliary fastened to each bracket member; a hanger passing over the top of the boiler shell and connected at each end to one of the members; and a tie-bar passing under the bottom of the boiler shell and connected at each end to one of the members.

17. In a locomotive, the combination of a boiler shell; a bracket member disposed outside of the boiler; an auxiliary member attached to the bracket member; a hanger bracket attached to the boiler shell; and a hanger connected to one of the members and the hanger bracket.

18. In a locomotive, the combination of a boiler shell; an auxiliary disposed outside of the boiler shell; a bracket secured to the shell; a hanger above the auxiliary attached at its end remote from the auxiliary to the bracket with the capacity to swing at its opposite end and carrying at least a portion of the weight of the auxiliary, whereby the

hanger will be under tension strain only, when supporting weight of the auxiliary; and means disposed below the hanger to prevent its swinging, but leaving the hanger free to act under tension strain only.

5 19. In a locomotive, the combination of a boiler shell; a bracket on one side of the shell; a hanger secured to the bracket, and passing over the top of the shell to the other side
10 thereof; and an auxiliary disposed outside of the boiler at said last mentioned side carried at least in part by said hanger.

15 20. In a locomotive, the combination of a boiler shell; auxiliaries disposed outside of the boiler shell, at least one on each side thereof; means disposed above the auxiliaries, supported by the boiler shell, and carrying at least a portion of the weight of the auxiliaries; and means passing under the bottom of
20 the boiler shell and cooperating with the said carrying means to maintain the said auxiliaries in fixed positions.
